UNITED STATES PATENT OFFICE.

LORENZO NORVELL, OF ST. LOUIS, MISSOURI.

AUTOMOBILE-HOOD.

1,365,121.

Specification of Letters Patent. Patented Jan. 11, 1921.

Application filed October 8, 1919. Serial No. 329,233.

To all whom it may concern:

Be it known that I, LORENZO NORVELL, a citizen of the United States of America, residing at the city of St. Louis, State of Missouri, United States of America, have invented a certain new and useful Automobile-Hood, of which the following is such a full, clear, and exact description as will enable any one skilled in the art to which it appertains to make and use the same, reference being had to the accompanying drawings, forming part of this specification.

My prior Patent No. 1,226,576 describes means for insulating automobile hoods which comprises applying removable sections of insulating material to the inner surfaces of the sections of the hood. The present invention relates to improved clamping means for quickly and removably attaching the insulating sections to the hood sections without the necessity of making any openings in the hood sections and without the use of rivets or bolts.

In the accompanying drawings, which illustrate my improved clamping means Figure 1 is a side view of an automobile hood of common construction, and showing the position of the clamps; Fig. 2 is a cross section along the line 2—2 of Fig. 1; Fig. 3 is a view similar to Fig. 2, but illustrating a modified form of clamp; and Fig. 4 is an enlarged view showing two of the clamps of Fig. 2 more in detail.

In the usual automobile hood construction 1, the edges of sections of the hood are provided with spaced extensions, which extensions are bent into circular shape to form hinge members, the extensions on the edge of one hood section alternating with the extensions on the edge of the adjacent hood section whereby the axes of these extensions can be brought into line and the hinge rod or pivot 6 inserted. In Fig. 1, the extensions on the upper edge of one of the upper hood sections are indicated by the numerals 3 and those on the upper edge of the adjacent upper hood section by the numerals 4.

A removable insulating section 5 of asbestos board or other suitable material is provided for each of the hood sections and it is to means for holding these insulating sections in position that this invention is particularly directed. The hood sections are usually provided with inwardly turned stiffening flanges 7 between the extensions

which form the hinge members (see Fig. 4), and my improved clamp comprises a strip of bendable material, preferably steel, which embraces a down turned flange 7, and extends through the space between a hinge member on the adjacent hood section and the hood section carrying the flange. The upper end of the clamp bears upon the outer surface of the hood section and the lower end is bent in a direction substantially parallel to the hood section, and in a position to form a space between it and said hood section for the reception of the edge of the insulating section 5.

It will be noted that the arrangement of the clamp is such with respect to the surfaces of the flange and the hood section that when the clamp is bent into position it is held against removal by opposing surfaces only and without rivets or other independent means of attachment. Clamps 2 may be positioned wherever desired, it being sufficient to have two or three of these on each edge of each hood section where it is hinged to another section. Clamps 8, riveted to the lower edges of the lower insulating sections, and having one end inserted behind the inturned edges 9 of the lower hood sections serve to hold the lower edges of the lower insulating sections in position.

In lieu of the clamps 2 heretofore described the form of clamp 10 illustrated in Fig. 3 may be substituted in cases where the hood sections are not provided with flanges, such as 7. As will be apparent from the drawings, the clamps 10 are riveted to the insulating sections 5 and passed through the same openings as in the case of clamp 2 finally being bent down to embrace outer portions of the hood sections. The lower edges of the lower insulating sections may be held by clamps such as 11 in instances where the lower edges of the lower hood sections are turned outward as in Fig. 3 instead of inward as in Fig. 2.

The advantages of my improved clamping means lie in cheapness and simplicity, and particularly in the ease of installation and removal of the insulating sections, it being unnecessary to drill any holes in the hood section to provide means for holding the insulating sections in place.

Having fully described my invention what I claim and desire to secure by Letters Patent of the United States is:

1. The combination with an automobile

- hood formed in sections, of sections of insulating material for the hood sections, and clamps of bendable material extending around edges of the hood sections and adapted to hold the insulating sections in position.
2. The combination with an automobile hood formed in sections having spaced extensions forming hinge members, sections 10 of insulating material for the hood sections, and clamps of bendable material for holding the insulating sections in position each embracing a portion of the outer surface of a hood section, said clamps passing 15 around edges of the hood sections between spaced extensions forming hinge members.

3. The combination with an automobile hood formed in sections having spaced extensions forming hinge members and inwardly projecting flanges between the hinge members, sections of insulating material for the hood sections, and clamps of bendable material embracing a portion of an insulating section and a portion of the outer surface of a hood section, said clamps also embracing opposite sides of one of the aforesaid flanges on a hood section whereby the clamps are held in position by opposing surfaces.

In testimony whereof I have hereunto set 30 my hand and affixed my seal.

LORENZO NORVELL. [L.S.]
